UNITED STATES PATENT OFFICE

172,355

SOAP STONE CRAYON HOLDER

Carl G. Zimmer, Worcester, Mass.

Application May 18, 1953, Serial No. 25,032

Term of patent 14 years

(Cl. D74—21)

To all whom it may concern:

Be it known that I, Carl G. Zimmer, a citizen of the United States and a resident of the city of Worcester, State of Massachusetts, have invented a new, original, and ornamental Design for a Soap Stone Crayon Holder, of which the following is a specification, reference being had to the accompanying drawings in which

Fig. 1 is a perspective view of a soap stone crayon holder, showing my new design;

Fig. 2 is a side elevational view, and

Fig. 3 is a top view thereof.

I claim:

The ornamental design for a soap stone crayon holder, as shown.
